DAVIS BARNARD, OF APPLE VALLEY, CALIFORNIA.

PUMP PLUNGER.

Application filed February 14, 1923, Serial No. 618,918. Renewed March 24, 1928.

This invention relates to pump plungers employed in well pumps and is particularly applicable to double stroke pumps.

The double stroke pump such as employed in deep well pumping employs a pair of buckets or plungers which move in opposite directions so that one plunger is travelling upwardly while the other travels downwardly, thus preserving a continuous flow from the well. The plungers employed for this purpose are customarily provided with cup shaped gaskets of fibrous material such as those, commonly designated as cup leathers, which are mounted with the lips thereof disposed upwardly so that the weight of the water being pumped therewith causes the lip to engage the wall of the pump barrel and thus provide a good working seal so that little loss is encountered due to the leakage of water by the plunger.

These cup leathers are formed from sheet leather and provide a circular ring having a lip or cylindrical portion bent upwardly around the edges thereof. This formation results in a curved corner where the ring portion of the cup leather meets the cylindrical portion thereof. The buckets or plungers in the form in which they are now employed provide cylindrical heads having cup leathers mounted upon the cylindrical face thereof by means of spacing rings or screw rings between which the ring portions of the gaskets are gripped. Sand is encountered in varying degrees in a majority of wells and constitutes a source of trouble to the pump plunger. During the downward stroke of the plunger, sand enters between the face of the pump barrel and the outer face of the cup gaskets, owing to the fact that the gaskets are rounded at the corner where the cylindrical or lip portion thereof meets the ring portion, thus providing a rounded corner engagement between the gasket and a pump barrel between which the sand may readily enter during the downward stroke thereof. This sand imbeds itself in the outer face of the cup leathers and causes excessive wear upon the pump barrel and likewise excessive friction therebetween. Sand also works down between the inner face of the lip portion of the cup leathers and the cylindrical face of the head upon which they are mounted and wedging therein forces the leathers outwardly against the pump barrel wall and causes

excessive friction and wear between the cup leathers and the pump barrel. It is customary to provide a valve in the plunger and a number of cup leathers disposed down the surface thereof. This construction results in excessive pressure being exerted, by the head of the water lifted, upon the upper cup leather so that the wear thereof is much more rapid than is the wear of the following cup leathers.

It is an object of my invention to provide a pump plunger which will not sand up, and thus cannot become frozen in the pump barrel.

It is also an object of the invention to provide in such a plunger means for preventing the entrance of sand between the cup leathers and the face of the pump barrel.

It is a further object of the invention to provide a plunger in which the load of the head being lifted is evenly distributed throughout the successive cup leathers.

It is a further object of the invention to provide a valve closure member and pump plunger which rotates slightly at each operation thereof so that an even wear with the valve seat is accomplished.

For the purpose of preventing the entrance of sand between the cup leather and the pump barrel, a downwardly directed cup gasket is employed in combination with the upwardly directed cup gaskets so that a scraping contact is provided with the interior wall of the pump barrel during the downward stroke of the plunger, thus removing adhering sand from the barrel wall and preventing the entrance of sand between the cup gasket and the barrel wall which may imbed in the outer face of the cup gaskets and thus cause excessive wear. The plunger is comprised of consecutively arranged valve members which are linked together, so as to provide unitary action or movement thereof, by interconnecting rods which serve as cages or guides for the closure members. Each of these valve members is provided with an upwardly directed cup gasket which extends above the top face of the valve member and therefore does not provide an annular groove between the valve member and the inner face of the cup gasket lip between which sand may accumulate. Below each of the upwardly turned cup gaskets a downwardly directed cup gasket is placed which makes scraping

contact with the pump barrel wall during the downward movement of the plunger, and each of the mentioned gaskets is preferably initially provided with a continuous and acute outer edge, as shown.

One form of the invention provides a centrally disposed sleeve through which a pump rod may extend to the lower pump plunger. Around this sleeve a valve closure member is mounted which has vanes associated therewith for causing the rotation of the closure member when it is lifted by the inflow of liquid.

It is a further object of the invention to provide a gasket supporting member which is made in the form of a ring having lips at the outer edge thereof which adhere to the curvature presented by the corner of the cup gasket.

The especial advantages of my invention and further objects thereof will be made evident hereinafter.

Referring to the drawings, which are for illustrative purposes only,

Fig. 1 is a diagrammatic section showing one use to which a plunger embodying the features of my invention is adapted.

Fig. 2 is a vertical section through the upper pump plunger shown in Fig. 1.

Fig. 3 is a section taken upon a plane represented by the line 3—3 of Fig. 2.

Fig. 4 is a section taken upon a plane represented by the line 4—4 of Fig. 2.

Fig. 5 is an enlarged fragmentary sectioned detail showing the stuffing box located at the lower end of the rod carrying sleeve and also showing a rod having an exterior brass wearing facing thereupon.

Fig. 6 is a vertical section through the lower pump plunger shown in Fig. 1.

Fig. 7 is a section on a plane represented by the line 7—7 of Fig. 6.

In double stroke deep well pumps, it is customary as shown in Fig. 1 to employ an upper plunger 11 which is supported and reciprocated within a pump barrel 12 by a tubular shaft 13 in which there extends a pump rod 14. This pump rod 14 extends through the plunger 11 and supports a lower pump plunger 15. Mechanism provided at the mouth of the well is employed for reciprocating the pump plungers in opposite directions so that as the upper plunger 11 is moving downwardly, the column of water in the well tubing is being raised by the upward movement of the lower plunger 15, and likewise when the lower plunger 15 moves downwardly, the upper plunger 11 lifts the column of water.

In Fig. 2 of the drawing, I show my invention adapted to the construction of the upper pump plunger shown at 11 in Fig. 1. This pump plunger provides a number of valve members 17 which are consecutively arranged as shown and are composed of upper and

lower valve plates 18 and 19 which clamp the ring or base portions 20 of cup gaskets 21 against an annular supporting member 22 which is provided with oppositely extending lips 23 which curve inwardly as indicated at 70

so that they fit closely to the rounded corner provided between the ring portion 20 and the lip or cylindrical portion 25 of the cup gaskets 21. These plates 18 and 19 are initially secured together by screws or other suitable binding means 27 and are later clamped between the ends of spacing members 28 through which rods 29 extend. The upper ends of the rods 29 extend through a suspension member, or spider, 31 which is provided with a threaded opening 32 into which the tubular shaft 13 by which the plunger is supported may be screwed as shown. A central supporting plate 34 may be provided between the valve members 17 and a spider 35 may

be employed to support the lower ends of the rods in the circular arrangement in which they are preferably disposed around the central axis of the plunger. Extending downwardly from the suspension member 31 through the openings 36 in the valve members 17 is a pump rod carrying sleeve 38 which is secured to the central supporting member 34 and to the lower spider 35 by means of suitable threaded engagement and clamp nuts 39. Above each of the valve members 17 a valve closure member 40 is placed, each of which is provided with a central opening 41 so that the sleeve 38 may extend therethrough.

It will be noticed that the opening 41 of each member 40 is somewhat larger in diameter than the sleeve 38 and that a sleeve 43 extends downwardly therefrom. The sleeves 42 are inwardly beveled at their lower ends 105 and seat against conical closure members 43 which are adjustably mounted upon the sleeve 38 and secured by clamp nuts. Radial holes 44 communicate between the opening 41 and the cylindrical channel 45 formed in the closure member 40. As shown in Figs. 3 and 4, vanes 46 are disposed in the channels 45 and before the openings 44 so that when the closure member 40 is lifted and water or other fluid being pumped flows up through the tubular member 42 it is directed outwardly through the openings 44 due to the inwardly directed lips 47 formed at the top of the openings 41. These jets of water from the openings 44 strike against the vanes 46, as indicated by the arrows 49 in Fig. 4, and impart a rotative force to the closure members which are caused to turn slightly so that when they again drop upon the seats provided in the upper rings 18, they will assume a different relative position, therefore causing an equal distribution of wear between the closure members and the valve members.

It will be noted that the lips 25 of the upwardly directed cup gaskets extend above the 130

members 18 and that the supporting rods are spaced inwardly away from the inner face of the lip 25, thus leaving an ample space there-between through which water may circulate 5 when it flows upwardly through the openings 36 in the valve member 17 and is deflected outwardly due to the presence of the closure members. This inflowing water washes out whatever sand may collect upon the plate 18 and prevents its packing against the cup leathers and thus forcing them outwardly. This packing of sand against the cup leathers is otherwise prevented due to the fact that the construction provides no crevice into 15 which the sand may enter and such sand as may collect could only rest against the inner face of the lip 25 due to the fact that there is no cooperating wall such as provided in the present type of pump bucket against which 20 the sand may react to force the lip of the cup gaskets outwardly. Any collection of sand will, however, be necessarily very small owing to the washing action of the inflowing water during the downward stroke of the 25 plunger. The sleeves 28 mounted upon the rods 29 provide a cage structure for the valve members.

It will be noticed that each of the valve members 40 is of but slightly smaller external 30 diameter than the circle defined by the inner faces of the sleeves 28. The closure members 40 are therefore guided by the sleeves and do not engage the threads formed upon the central sleeve 38.

35 The rod 14 by which the lower plunger 15 is actuated extends centrally within the tubular shaft 13 and through the sleeve 38 which is provided with a packing member 50 at its lower end, as shown in Fig. 5. That 40 portion of the rod 14 which extends through the sleeve 38 is provided with a brass covering 51 so that the wearing surfaces of the rod will be of reduced frictional characteristics. In order to prevent the entrance of sand into 45 the packing member 50, the plunger 11 is so constructed that the upper end of the sleeve 38 is in liquid tight communication with the threaded opening 32. The tubular shaft 13 is filled with oil which, although of slightly 50 lighter weight than water, exerts a reacting pressure within the sleeve 38 and the stuffing box 50 which prevents the entrance of sand due to difference in pressure between the interior and exterior of the sleeve.

55 In Figs. 6 and 7, the principles of my invention are shown applied to the lower pump plunger 15. This pump plunger, although shown in use as the lower member of a double stroke pump, is suitable for use in single acting water pumps and is found suitable for pumping of oil. Valve members 60 similar to those shown in Fig. 1 are connected together in consecutive arrangement by rods 61 and spacers 62. The upper ends of the rods 65 screw into a ring member 63 which cooperates

with a head 64 and bars 65 in forming a suspension member 66. In this type of plunger, nuts 68 and lock nuts 69 may be employed upon the lower ends of the rods 61 instead of a spider as shown in Fig. 1 at 46. Also, in this 70 plunger the closure members 40 are replaced by balls 70 which seat in the openings of the valve plates 71. The upwardly directed cup gasket 73 of each valve member 60 provides a lip which is in scraping engagement with the pump barrel wall when the plunger travels upwardly. It will be recognized that any sand adhering to the pump barrel wall will be scraped off by the cup gaskets and will not enter between the face of the gasket and 75 the wall of the pump barrel. During the downward stroke of the plunger, the downwardly directed cup gaskets 75 remove the sand from the wall of the pump barrel head of the downwardly moving piston and also 80 prevent the passage of water, which might have sand in suspension therein, upwardly between the gaskets and the pump barrel wall. Therefore, all movement of water must be 85 through the openings in the valve members 90 which assures that no sand will be deposited upon the wearing faces of the cup gaskets.

In the ordinary type of pump bucket, only one valve is provided in the plunger and a greater portion of the weight of the head of 95 water being lifted must be supported upon the upper cup gasket thereof. My invention provides a number of valve members each having cup gaskets mounted thereupon which valve members are spaced apart but move 100 simultaneously owing to the interconnecting cage structure. During the downward stroke of a plunger so constructed, the valve balls 70 are raised and water passes freely through the openings in the valve members. As the 105 plunger starts upwardly from the lowest position, the weight of the head of water carried by the plunger is distributed between the separate valve members so that the entire pressure thereof is not carried by the upper 110 cup gasket. This arrangement adds very greatly to the efficiency and also to the durability of the pump plunger as will be readily recognized. It will be noticed in the plunger 115 shown in Fig. 6 that the cage structure provided by the rods is spaced somewhat away from the inner face 80 of the cup gaskets and that the lips of the cup gaskets extend beyond the plates 71 between which they are clamped, therefore preventing the wedging 120 of sand against the cup gaskets.

I claim as my invention:

1. In a pump plunger, the combination of: a valve seat; a valve co-acting with said valve seat; an upwardly disposed cup gasket for scraping the pump barrel wall on the upward stroke of said plunger; a downwardly disposed cup gasket for scraping the pump barrel wall on the downward stroke of said plunger; means for rigidly securing said cups 125 130

together adjacent said valve seat, both of said cup gaskets being in communication with the valve seat opening when the valve is in open position; and means for rotating said valve on each downward stroke of said plunger.

2. In a pump plunger, the combination of: a substantially flat valve member; a closure member cooperating with said valve member; a cup gasket so supported upon said valve member that the lip thereof extends upwardly around and above the top face of said valve member; a cage structure for enclosing said closure member, said cage structure being spaced away from the inner face of said lip; and means between which said closure member is movable whereby said closure member is rotated at each operation thereof.

3. In a pump plunger, the combination of: a substantially flat valve member having an opening therethrough; a rod carrying sleeve extending through said opening; a closure member adapted to close said opening, said closure member having an opening therethrough through which said sleeve extends; a sleeve extending downwardly from the mouth of said opening through said closure member and around said rod carrying sleeve; and a member mounted upon said rod carrying sleeve for closing the lower end of said sleeve extending from said closure member.

4. In a pump plunger, the combination of: a valve member having an opening therethrough; a rod carrying sleeve extending through said opening; a closure member adapted to close said opening, said closure member having an opening therethrough through which said sleeve extends, and radial openings communicating with said opening through which said sleeve passes; vanes mounted in such a manner that water passing through said radial openings will strike thereagainst and cause rotation of said closure member; a sleeve extending downwardly from the mouth of said opening through said closure member and around said rod carrying sleeve; and a member mounted upon said rod carrying sleeve for closing the lower end of said sleeve extending from said closure member.

5. In a pump plunger, the combination of: a valve member having an opening therethrough; a rod carrying sleeve extending through said opening; a closure member adapted to close said opening, said closure member having an opening therethrough through which said sleeve extends; a sleeve extending downwardly from the mouth of said opening through said closure member and around said rod carrying sleeve; a member mounted upon said rod carrying sleeve for closing the lower end of said sleeve extending from said closure member; a cup gasket so mounted upon said valve member that the lip thereof extends upwardly around and above the top face of said valve member; and

a cage structure upon said valve member, said cage structure being spaced away from the inner face of said lip.

6. In a pump plunger, the combination of: a valve member having an opening therethrough; a rod carrying sleeve extending through said opening; a closure member adapted to close said opening, said closure member having an opening therethrough through which said sleeve extends, and radial openings communicating with said opening through which said sleeve passes; vanes mounted in such a manner that water passing through said radial openings will strike thereagainst and cause rotation of said closure member; a sleeve extending downwardly from the mouth of said opening through said closure member and around said rod carrying sleeve; a member mounted upon said rod carrying sleeve for closing the lower end of said sleeve extending from said closure member; a cup gasket so mounted upon said valve member that the lip thereof extends upwardly around and above the top face of said valve member; and a cage structure upon said valve member, said cage structure being spaced away from the inner face of said lip.

7. In a pump plunger, the combination of: a valve member having an opening therethrough; a rod carrying sleeve extending through said opening; a closure member adapted to close said opening, said closure member having an opening therethrough through which said sleeve extends, and radial openings communicating with said opening through which said sleeve passes; vanes mounted in such a manner that water passing through said radial openings will strike thereagainst and cause rotation of said closure member; a sleeve extending downwardly from the mouth of said opening through said closure member and around said rod carrying sleeve; a member mounted upon said rod carrying sleeve for closing the lower end of said sleeve extending from said closure member; a cup gasket so mounted upon said valve member that the lip thereof extends upwardly around and above the top face of said valve member; suspension and cage forming rods mounted in circular arrangement upon said valve member; and suspension means attached to the upper ends of said rods.

8. In a pump plunger, the combination of: a valve member having an opening therethrough; a rod carrying sleeve extending through said opening; a closure member adapted to close said opening, said closure member having an opening therethrough through which said sleeve extends, and radial openings communicating with said opening through which said sleeve passes; vanes mounted in such a manner that water passing through said radial openings will strike

thereagainst and cause rotation of said closure member; a sleeve extending downwardly from the mouth of said opening through said closure member and around said rod carrying sleeve; a member mounted upon said rod carrying sleeve for closing the lower end of said sleeve extending from said closure member; a cup gasket so mounted upon said valve member that the lip thereof extends upwardly around and above the top face of said valve member; and suspension and cage forming rods mounted in circular arrangement upon said valve member, said rods being spaced away from the inner face of said lip.

15 9. In a pump plunger, the combination of: a valve member having an opening therethrough; a rod carrying sleeve extending through said opening; a closure member adapted to close said opening, said closure member having an opening therethrough through which said sleeve extends; a sleeve extending downwardly from the mouth of said opening through said closure member and around said rod carrying sleeve; a member mounted upon said rod carrying sleeve for closing the lower end of said sleeve extending from said closure member; a cup gasket so mounted upon said valve member that the lip thereof extends upwardly around and above the top face of said valve member; a cup gasket mounted upon said valve member, at a point below said upwardly directed cup gasket, and being downwardly directed so as to scrape the pump barrel wall as said plunger moves downwardly; and a cage structure upon said valve member, said cage structure being spaced away from the inner face of said lip.

20 10. In a pump plunger, the combination of: a valve member having an opening therethrough; a rod carrying sleeve extending through said opening; a closure member adapted to close said opening, said closure member having an opening therethrough through which said sleeve extends, and radial openings communicating with said opening through which said sleeve passes; vanes mounted in such a manner that water passing through said radial openings will strike thereagainst and cause rotation of said closure member; a sleeve extending downwardly from the mouth of said opening through said closure member and around said rod carrying sleeve; a member mounted upon said rod carrying sleeve for closing the lower end of said sleeve extending from said closure member; a cup gasket so mounted upon said valve member that the lip thereof extends upwardly around and above the top face of said valve member; a gasket upon said valve member at a point below said cup gasket for scraping the pump barrel wall as said plunger moves downwardly; and suspension and cage forming rods mounted in circular arrangement upon said valve member, said

rods being spaced away from the inner face of said lip.

11. In a pump plunger, the combination of: a valve member having an opening therethrough; a rod carrying sleeve extending through said opening; a closure member adapted to close said opening, said closure member having an opening therethrough through which said sleeve extends; a sleeve extending downwardly from the mouth of said opening through said closure member and around said rod carrying sleeve; a member mounted upon said rod carrying sleeve for closing the lower end of said sleeve extending from said closure member; a cup gasket so mounted upon said valve member that the lip thereof extends upwardly around and above the top face of said valve member; a cup gasket mounted upon said valve member, at a point below said upwardly directed cup gasket, and being downwardly directed so as to scrape the pump barrel wall as said plunger moves downwardly; and a cage structure upon said valve member, said cage structure being spaced away from the inner face of said lip.

15 12. In a pump plunger, the combination of: a plurality of valve members, consecutively arranged with spaces therebetween; and means, comprising rods provided with sleeves, linking said valve members so that they operate as a unit.

13. In a pump plunger, the combination of: a plurality of valve members having gaskets thereupon for engagement with the pump barrel wall, and being consecutively arranged with spaces therebetween; and means, comprising rods provided with sleeves, linking said valve members so that they operate as a unit.

18 14. In a pump plunger, the combination of: a plurality of valve members each having a downwardly directed cup gasket thereupon for scraping the pump barrel walls during downward movement, and being consecutively arranged with spaces therebetween; and means, comprising rods provided with sleeves, linking said valve members so that they operate as a unit.

19 15. In a pump plunger, the combination of: a plurality of valve members each having an upwardly directed cup gasket thereupon and a downwardly directed cup gasket thereupon for scraping the pump barrel walls during downward movement, and being consecutively arranged with spaces therebetween; and means, comprising rods provided with sleeves, linking said valve members so that they operate as a unit.

In testimony whereof, I have hereunto set my hand at Los Angeles, California, this 9th day of February, 1923.

DAVIS BARNARD.
